CLAIM

The ornamental design for an artistic lamp as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1.1 is a perspective view of the lamp showing my new design;

FIG. 1.2 is a second perspective view thereof;

FIG. 1.3 is a top view thereof;

FIG. 1.4 is a side view thereof;

FIG. 1.5 is a second side view thereof;

FIG. 1.6 is a bottom view thereof; and

FIG. 1.7 is an exploded perspective view thereof.

The interior portions of the lamp shown in the reproductions 1.1 to 1.7 form no part of the claimed design.

1 Claim, 7 Drawing Sheets
